UNITED STATES PATENT OFFICE

HANS C. JORDHOY, OF NORTH PLAINFIELD, NEW JERSEY, ASSIGNOR TO WOOD NEWS-PAPER MACHINERY CORPORATION, OF NEW YORK, N. Y., A CORPORATION OF VIRGINIA

CUTTING COUPLE

Application filed August 31, 1927, Serial No. 216,722. Renewed June 12, 1930.

This invention relates to the cutting and folding cylinders of a folder for newspaper printing presses and the like.

The principal objects of this invention are 5 to provide a new arrangement of the cutting blades by which the cutting off of the edge of the first sheet of paper when the second is cut, in collecting, and the production of waste commonly known as "sauerkraut" is 10 avoided; to provide means for accomplishing this result by cutting long and short sheets alternately, either by shifting the knife on the cutting cylinder so that each alternate sheet will be cut longer than the 15 previous one, or by placing two cutting knives on the larger or folding cylinder so related to each other as to divide the circumference unevenly into two parts, and to provide means for operating these parts, particularly the shifting knife in an accurate 20 and positive manner. The invention also involves improvements in details of construction and combinations of parts as will appear.

25 Reference is to be had to the accompanying drawings, in which

Fig. 1 is an end view partly in section of a cutting cylinder showing its relation to the adjacent folding cylinder and constructed in 30 accordance with this invention;

Fig. 2 is a sectional view of the same on the broken line 2-2 of Fig. 1;

Fig. 3 is a transverse sectional view on the line 3-3 of Fig. 2;

Fig. 4 is a sectional view on the line 4-4 of Fig. 3; and

Fig. 5 is an end view of a folding and cutting couple showing the invention applied thereto in a modified way.

40 In the conventional printing press the papers that had been printed and associated over the former are cut into sheets between a pair of cutting cylinders, one of which has a circumference of one page carrying the cutting knife and the other has a circumference of two pages carrying the cutting rubbers. When it is desired to collect the two adjacent papers on top of one another, the first is wrapped completely around the small cutting cylinder and is associated with the

succeeding paper at the moment of cutting the latter, after which both are carried around the large folding cylinder, from which they are tucked into a pair of folding rollers by a suitable folding blade. Since 55 the first paper is already cut at its leading edge, when the latter is made to register with the leading edge of the succeeding paper, there is danger of a certain portion of that edge being cut off from the paper when the 60 second cut is made, thereby producing waste strips, commonly known as sauerkraut.

In the form of the invention shown on the first two sheets, the cutting cylinder 10 has the usual relation to the folding cylinder 11, the latter having a rubber 12 for receiving the cutting blade, but in this case this rubber is provided with two grooves 13 instead of one as usual, the purpose of which will appear 70 later.

For the purpose of cutting long and short sheets alternately I place the cutting knife 14 in a knife box 15 in the cylinder 10. This knife box is located in a recess 16 in this cylinder and mounted on a pivot stud 17 near the center so that it can swing from the position shown in Fig. 1 back to a position in which the opposite side of the knife box 15 engages the opposite side of the recess. It will be noticed that the knife 14 is shown as entering 75 one of the grooves 13 in this figure. When the knife box is shifted back as just described, the same blade will enter the other groove 80 13. The object of this is to provide that during the first revolution illustrated in Fig. 1, when the paper wrapped around the cylinder 10 is cut from the web, the knife box with its cutting knife is held in the position shown. It is moved to the opposite position during 85 the subsequent rotation of this cylinder 10 so that every other sheet that it cuts will be longer than the preceding one.

The movement of the knife box is accomplished in the following manner: At the end 95 of the knife box is a projecting lug 20. This engages in a radial slot 21 in a ring 22 which is mounted around the shaft of the cutting cylinder at that end, but is capable of independent oscillating motion thereon. This motion is imparted to the ring by the action 100

of an auxiliary crank 23 pivoted on the face of the cylinder on a longitudinal rod 24 and provided with three rollers 25, 26 and 26. The two rollers 26 engage opposite sides of a slot 27 cut in the face of the ring 22. This slot is formed with substantially flat sides extending from the outside toward the center and tangent to a substantially central circle. In other words, they diverge from radial position. The roller 25 rides in the path of a cam 29. This is the pin rod cam and actuates the pin rod 30 to reciprocate the pins 31 through an arm 32 on this rod. The arm 32 has a roll 33 also engaging in the cam 29 as usual.

It will be understood that an eccentrically mounted shaft 35 is provided with two gears 36 and 37 which can be moved into and out of mesh with gears 38 and 40 by the eccentric 46. The larger of these gears meshes with the gear 38 on the shaft 39 of the cutting cylinder. The smaller gear 37 meshes with the gear 40, carried by a bushing 41 free on the shaft 39. The hub of the gear 40 and the cam 29 are fixed and are shown as integral. This gear 40 is larger than the gear 37 and the gear 36 is larger than the gear 38 as shown. The gear ratio is such that for each two rotations of the shaft 39 there will be one rotation of the cam 29. The gearing shown is conventional.

The pins emerge from the cylinder during the first rotation carrying the paper around the cylinder and withdraw during the second rotation, permitting the paper around the cylinder to be picked off by similar pins on the folding cylinder as usual. I utilize the cam 29 of the pin motion to impart the oscillating motion through the crank 23 to rock the knife box 15 back and forth at each alternate revolution of the cutting cylinder. Therefore, on the first rotation of the cutting cylinder the sheet going around it will be cut at the point indicated by the position of the blade 14 in Fig. 1. On the next rotation it will be cut at the other groove 13, at which point the knife will be located at that time by the means above mentioned. Therefore, every second sheet will be longer than the preceding one. In this way two adjacent papers will be collected on top of one another with the first wrapped around the cylinder 10 and associated with the succeeding paper at the moment of cutting the latter, without any danger of the latter cutting motion producing the so-called sauerkraut, because the cutting line is beyond the end of the first sheet.

The invention also can be carried out in the form shown in Fig. 5, in which the mechanism is somewhat simpler, and involves the use of two knives 44 on the folding cylinder 11 and the cutting rubber 42 on the cutting cylinder 10. This rubber also has two grooves 43 at a distance apart and the two

knives 44 are placed out of diametrical alignment with each other. In other words there is a wider space between them circumferentially on one side than on the other. This causes each alternate sheet to be cut slightly longer than the one preceding it as in the form shown in Fig. 1. This effectively eliminates the danger of cutting waste from the preceding sheet as the second knife cuts at a point beyond the previously cut edge of the first sheet as in the other form shown.

It will be seen, therefore, that with both of these forms of the invention the same object is accomplished and the waste known as sauerkraut is entirely eliminated, no occasion arising of its being cut from the first sheet at any time. The mechanism is not unduly expensive in view of the advantages secured.

Although I have illustrated and described only two forms of the invention, I am aware of the fact that changes can be made therein by any person skilled in the art without departing from the scope of the invention as expressed in the claims. Therefore, I do not wish to be limited to the exact forms shown, but what I do claim is:

1. In a folding and cutting couple, the combination with a folding cylinder and a cutting cylinder, of means carried by said cylinders for cutting successive sheets of alternating different lengths from a web, said means being located and arranged so that the cutting operation on the first of two successive sheets is performed at one spot on the circumference and the cutting operation on the second sheet is performed at another point along the circumference, for the purpose described.

2. In a folding and cutting couple, the combination with a folding cylinder and a cutting cylinder, of means carried by said cylinders whereby a cutting operation on the first of two successive sheets is performed at one spot on the circumference and a cutting operation on the second sheet is performed at another point on the circumference for the purpose described.

3. In a cutting and folding couple, the combination with a cutting and folding cylinder, one having a cutting rubber thereon and the other a cutting blade cooperating therewith, said cutting rubber having two grooves at a distance apart circumferentially for receiving the cutting blade, and means whereby on successive cuts the cutting blade will engage the rubber alternately in the two grooves.

4. In a cutting and folding couple, the combination with a folding cylinder and a cutting cylinder, of a cutting rubber carried by one of said cylinders having two longitudinal grooves therein circumferentially spaced from each other, cutting means on the other cylinder for cooperating with said grooves, and means whereby when two sheets are to be associated the cutting means will

engage in one of said grooves to cut the first sheet and will engage in the other groove, located farther around the circumference, to cut the second sheet longer than the first sheet.

5. In a cutting and folding couple, the combination with a folding cylinder and a cutting cylinder, of cutting means carried by one of said cylinders, and means whereby when two sheets are to be associated the cutting means will engage the other cylinder to cut the first sheet and will engage the other cylinder at a point farther around the circumference to cut the second sheet longer than the first sheet.

6. In a cutting couple, the combination with two cylinders, of a knife movably mounted on one of said cylinders, and means for shifting the knife between alternate operations of the couple to bring the cutting point at a different point around the circumference of the cylinder and change the length of the sheet cut.

7. In a cutting couple, the combination with two cylinders, of a knife box movably mounted on one of said cylinders, a knife carried by the knife box, and means for shifting the knife box about a longitudinal axis to change the cutting point along the circumference of the cylinder.

8. In a cutting couple, the combination with the two cylinders thereof, of a knife box carried by one of said cylinders and pivotally mounted therein, said cylinder having a recess for the knife box wider than the box, and means for oscillating said knife box on its pivot between cutting operations so that the cuts will be produced in two positions of the knife box and the sheets cut will be alternately a long and a short sheet.

9. In a cutting couple, the combination with a cutting and collecting cylinder, of a knife box pivotally mounted thereon and having a lug projecting from the end, a ring mounted at the end of the knife box and having a slot for receiving said lug, a pin-rod operating mechanism comprising a cam, and means operated by said cam for oscillating said ring and thus moving the knife box on its pivot.

10. The combination with a cutting and collecting cylinder, of a knife box movably mounted thereon having a cutting knife carried thereby, the knife box having a lug projecting from the end, a ring mounted to freely turn on the cylinder and having a radial slot for said lug, a crank arm carried by the cylinder, the ring being provided with a slot, and the crank arm with two rolls movable in said slot to oscillate the ring when the crank arm is turned, the crank-arm having another roll, a pin-rod cam having a groove in which said other roll is mounted to be operated thereby, and means for rotating

the cam one-half as fast as the cutting cylinder for the purpose described.

11. In a cutting and folding couple, the combination with a large cylinder and a small cylinder, the small cylinder having a cutting rubber thereon and the large cylinder having a pair of cutting blades for cooperating therewith, located nearly at diametrically opposite points, but offset therefrom, to produce papers alternately of different lengths.

In testimony whereof I have hereunto affixed my signature.

HANS C. JORDHOY.
